DESIGN FOR A MILK BOTTLE OR SIMILAR ARTICLE

Harry Ennever, Harrington Park, N. J.

Application February 16, 1937, Serial No. 67,687

Term of patent 7 years

To all whom it may concern:

Be it known that I, Harry Ennever, a citizen of the United States, residing at Harrington Park, in the county of Bergen and State of New Jersey, have invented a new, original, and ornamental Design for a Milk Bottle or Similar Article, of which the following is a specification, reference being had to the accompanying drawing, forming part thereof.

Fig. 1 is a front elevational view of a milk bottle showing my new design.

Fig. 2 is a top plan view of the same.

Fig. 3 is a horizontal cross-sectional view as on line 3—3 of Fig. 1.

I claim:

The ornamental design for a milk bottle, or similar article, substantially as shown.

HARRY ENNEVER.
